MATERIAL TREATING MACHINE

Robert W. Bender, Kansas City, Kans., and Curtis Voigtlander, Kansas City, Mo., assignors to Union Wire Rope Corporation, Kansas City, Mo.

Application January 19, 1942, Serial No. 427,228

3 Claims. (Cl. 205—14)

This invention relates to a machine for treating material and particularly to wire drawing by the continuous method wherein the material is drawn through a die by means of a rotating drum and thence passed on to a succession of dies and drums until the wire is drawn to the desired diameter.

One of the important aims of this invention is the provision of a material treating machine having a part for supporting a number of elements, which part is of unitary character and formed to be machined accurately and quickly.

The invention resides in several combinations and arrangements of parts, which shall be hereinafter described, and are specifically pointed out in the annexed claims, reference being had to the accompanying drawings wherein:

Fig. 1 is a fragmentary side elevational view of the wire drawing machine, embodying my invention, having a portion thereof broken away in order to show certain of the parts.

Fig. 2 is an inverted plan view of the machine having a portion of the bearing structure broken away to show the method of journaling the drive shaft, and also showing a portion of the shaft, bearing structure and housing, broken away to reveal the base upon which the shaft and associated structure are supported.

Fig. 3 is a plan view of the wire drawing machine.

Fig. 4 is an enlarged sectional view of the machine taken on line IV—IV of Fig. 3 and also partially shows, in diagrammatical form, the manner in which the machine is to be lubricated and cooled.

Fig. 5 is a fragmentary inverted plan view of a modified form of the shaft and bearing structure, parts being broken away to clearly reveal the same; and

Fig. 6 is a fragmentary view of another modified form of the shaft and bearing structure, showing a portion thereof in section.

In the type of machine as employed by applicant, it is necessary that the speed of drawing the wire, and hence, the rotation of the blocks, be increased as the wire is passed through successive dies. This speed must be in proportion to the elongation of the wire, and one of the objects of applicant's invention, is to attain this mode of operation with a minimum of apparatus and in a highly efficient manner.

One of the difficulties encountered in the design of such apparatus has been the provision of gear structure which may be suitably driven from a single prime mover, since the forces required

to rotate the drums are relatively large, it is necessary the structure employed be rigidly mounted in such manner that gear trains and the like, are held in tight engagement. To accomplish this end the blocks are preferably mounted on a long, heavy, reinforced, unitary bed, and are adapted to be rotated by gears which are preferably driven by pinions or the like mounted on a long shaft, which is in turn, rigidly secured to the aforesaid base.

It has been found desirable by the applicant, that the gear structure of each successive block be such that the gears are of substantially the same diameter or dimensions, whereby the same may be associated in such manner that a minimum amount of displacement of the parts will occur. Further, it is desirable to employ structure wherein the length of the gear train is reduced to a minimum.

20 A machine constructed to achieve these ends is shown in the accompanying drawings, wherein unitary frame 10 provides for the rotative support of a series of drums or blocks 12. As shown in Figs. 1 and 4, each block is provided with an extension 14. The wire to be drawn (not shown in the drawings), is initially pulled across guide pulley 16 and through die 18 where it is wound on block 12, passing upwardly around extension 14, and thence through eyelet 19 of guide 20. The wire then passes through pulley 24, which is held in place by support 22; from this pulley 24 the wire is drawn across guide pulley 16 and die 18 toward the next succeeding drum 12.

25 As best shown in Fig. 2, the prime mover is a motor 26 which is interconnected by means of drive connection 28, with one end of a segmented shaft 30. Shaft 30 has a worm gear 32 mounted upon each segment thereof.

30 Shaft 30 extends along the length of frame 10 and is positioned so that worms 32 will operably engage gears 34. Gears 34 are adapted to rotate blocks 12 in the conventional manner. The segmented shaft 30 is supported at intervals by means of bearings 38 which the journaled in collars 36. These collars 36 are supported by frame 10 upon bases 42.

35 The segments of shaft 30 are keyed at the ends thereof and are adapted to be joined by means of keyed sleeves 40 which are placed over the ends of said shaft 30.

40 Sleeves 40 are slightly loose-fitting on shaft 30 whereby flexibility is imparted to the shaft which facilitates assembly and reduces friction between the bearings and the shaft, thereby re-

ducing the power required to operate the machine.

Frame 10 is machined from a unitary piece of metal. The edges and bases 42 on the lower side thereof are machined together. After said edges and bases 42 have been properly planed, the entire top surface of frame 10 is machined to be parallel with respect to the underside of the frame. This procedure insures that the collars 36 may be positioned whereby to hold the shaft and gears supported therein in proper operative relationship with blocks 12.

As shown in Fig. 4, blocks 12 are supported upon a spindle 46. This spindle 46 is journaled by means of roller bearings 50 and is held in operative position by the interaction of shoulder 48 and bearings 50. Bearings 50 are carried by a supporting member 52 which is rigidly affixed to frame 10. Gear 34 is affixed to the free end of spindle 46.

Supporting members 52 are positioned by means of corresponding, opposed machined faces 72 and 74 of members 52 and frame 10 respectively. As previously mentioned, the machined surfaces on the top of frame 10 are trued with respect to the gearing beneath the frame, and in this manner, members 52 hold the spindle 46, and hence, gears 34, in proper operative relation with worm 32 at all times. This feature further makes for quick interchangeability of the blocks 12 when desired.

Drip pan 54 extends the length and across the underside of frame 10 and is positioned immediately below gears 32 and 34. At the lowest point of the drip pan 54 is affixed a trough 56. A cooling line 58 connects with trough 56 and extends to a cooling tank 66 of conventional character. Cooling line 58 then passes in circuitous fashion through tank 66 and on emerging therefrom, is connected to pump 60. Line 58 is then connected with a branch whereby oil or other liquid is distributed by means of pipes 64 to points throughout the machine requiring lubrication or cooling.

It is to be noted that each of said worms 32 have a pitch which is greater than the preceding worm as the finishing end of the machine is approached. Gears 34 are correspondingly cut whereby they are adapted to be rotated by one of the worms 32 associated therewith.

Figs. 5 and 6 show a modification of keyed shaft segments 44 whereby the same are adapted to engage the end of the preceding segment in

such manner that both segments may be rotatably supported by means of a single bearing structure 65.

Fig. 5 shows a keyed collar 63 which is formed as an integral part of shaft segment 44 and is adapted to interlock with the keyed end 62 of the preceding segment 44.

Fig. 6 shows a coupling 70 which is keyed to accept the ends of keyed segments 44. This coupling 70 is journaled within collars 36 mounted as previously shown in Fig. 2.

Having thus described the invention, what is claimed as new and desired to be secured by Letters Patent is:

1. In a machine for drawing wire, a unitary frame; a series of supporting members mounted on the frame; a block and spindle assembly rotatably carried by each member respectively; a gear on the spindle; a drive shaft having worms in mesh with the gears respectively; and a series of bearings for holding the drive shaft on the frame, said frame having a base for each bearing and a face for each supporting member, said faces projecting beyond the outer surface of the frame for simultaneous machining of the faces, said bases and the faces being on opposite sides of the frame, the surfaces thereof being in parallel relation whereby to insure operative disposition of the drive shaft and gear on the spindle.

2. A machine as described in claim 1 wherein the frame is provided with an opening for the reception of the spindle assembly and said gear, and wherein the face for each supporting member is at the marginal edge of the frame formed by said opening.

3. In a machine for drawing wire, a unitary frame; a series of supporting members mounted on the frame; a block and spindle assembly rotatably carried by each member respectively; a gear on the spindle, a drive shaft having worms in mesh with the gears respectively; and a series of bearings for holding the drive shaft on the frame, said frame having bases for the bearings in exposed aligned relation to each other for simultaneous machining of the bases, said frame having faces for the supporting members in exposed aligned relation to each other for simultaneous machining of the faces, said bases and faces being on opposite sides of the frame in parallel relation.
